[57] CLAIM

The ornamental design of a work station, as shown and described herein.

DESCRIPTION

FIG. 1 is a perspective view of a work station showing our new design;

FIG. 2 is a front perspective view thereof;

FIG. 3 is a front elevational view thereof;

FIG. 4 is a rear elevational view thereof;

FIG. 5 is a left side elevational view, the right side being a mirror image thereof;

FIG. 6 is a top plan view thereof;

FIG. 7 is a rear elevational view of a modified form of the work station shown in FIG. 1, the addition of the curved modesty panel being the only difference and the sides not shown being the same as that shown in FIGS. 1-6; and,

FIG. 8 is a left side elevational view thereof.
